UNITED STATES PATENT OFFICE

160,906

HOLDER FOR PLAYING CARDS

Leo Ungar, University City, Mo.

Application October 15, 1949, Serial No. 5,507

Term of patent 3½ years

(Cl. D34—13)

To all whom it may concern:

Be it known that I, Leo Ungar, a citizen of the United States, residing in the city of University City, county of St. Louis, State of Missouri, have invented a new, original, and ornamental Design for a Holder for Playing Cards, of which the following is a specification, reference being had to the accompanying drawing, forming a part thereof.

In the drawing:

Fig. 1 is a perspective view of a holder for playing cards, showing my new design;

Fig. 2 is a top plan view thereof;

Fig. 3 is a side elevational view thereof, and

Fig. 4 is an end elevational view thereof.

I claim:

The ornamental design for a holder for playing cards, substantially as shown.

LEO UNGAR.
